COMBINED COPYING CAMERA AND PRINT FINISHING CABINET OR THE LIKE

Charles P. Sippel, Jr., Villa Park, and Walter Wanielista,
Westchester, Ill., assignors to Robertson Photo-Me-
chanix, Inc., Chicago, Ill., a corporation of Illinois

Filed May 26, 1961, Ser. No. 65,352

Term of patent 14 years

(Cl. D61—1)

FIG. 1

FIG. 2

FIG. 1 is a front perspective view of a combined copying camera and print finishing cabinet or the like showing our new design; and

FIG. 2 is a rear elevational view thereof.

The side of the article not shown is substantially plain and unornamented.

The essential features of our design are shown in full lines in the drawings.

We claim:

A design for a combined copying camera and print finishing cabinet or the like, substantially as shown and described.
